CLAIM

The ornamental design for a mount for a digital media player, as shown and described.

DESCRIPTION

FIG. 1 is a perspective view of a mount for a digital media player, in an exploded condition.

FIG. 2 is a perspective view of a top, front and right side of the mount of FIG. 1.

FIG. 3 is a front view of the mount of FIG. 1.

FIG. 4 is a rear view of the mount of FIG. 1.

FIG. 5 is a top view of the mount of FIG. 1.

FIG. 6 is a bottom view of the mount of FIG. 1; and,

FIG. 7 is a right side view of the mount of FIG. 1, the left side view being a mirror image thereof.
